Inventor
Edward Steigerwald,

UNITED STATES PATENT OFFICE.

EDWARD STEIGERWALD, OF PHILADELPHIA, PENNSYLVANIA.

SCORE-KEEPING APPARATUS.

1,346,987.

Specification of Letters Patent. Patented July 20, 1920.

Application filed February 2, 1920. Serial No. 355,717.

To all whom it may concern:

Be it known that I, EDWARD STEIGERWALD, a citizen of the United States, residing at Philadelphia, in the county of Philadelphia and State of Pennsylvania, have invented 5 certain new and useful Improvements in Score-Keeping Apparatus, of which the following is a specification.

One object of my present invention is to 10 provide an improved means for use in connection with score keeping apparatus, such for example as that disclosed in my United States Patent No. 1,327,177 of January 6, 1920, which will show at a glance whether 15 the score indicated by said apparatus is plus or minus.

Another object is to make my invention of a simple and durable construction and so that it will not readily get out of order.

These objects, and other advantageous ends which will be described hereinafter, I attain in the following manner, reference being had to the accompanying drawings in which—

25 Figure 1 is a fragmentary top plan view showing a portion of score keeping apparatus such for example as the apparatus of my above mentioned patent and including my present invention in lieu of the plus and minus indicating device of the apparatus of said patent,

30 Figs. 2 and 3 are fragmentary inverted plan views of the structure shown in Fig. 1 and illustrating two positions of the plus and minus indicating means of my present invention,

35 Fig. 4 is a fragmentary section taken on the line 4—4 of Fig. 2,

40 Fig. 5 is a fragmentary section of similar character to Fig. 4 showing another position of the parts,

45 Fig. 6 is a fragmentary perspective view showing certain of the elements of my invention,

50 Fig. 7 is a view of one face of a slidable plate which forms a part of my invention,

55 Fig. 8 is a view of the opposite face of said plate, and

60 Fig. 9 is a section taken on the line 9—9 of Fig. 7.

Referring to the drawings, 10 represents a base plate having rotatably mounted thereon at its under side a dial 11, such for example as the dial 28 in my above mentioned patent; said dial being capable of being rotated under certain conditions by means of a knob

12 to which is connected an indicating finger 13 adapted to traverse graduations 14 on the upper face of the dial. The dial 11 is capable of being locked to the knob 12 by 60 lever mechanism 15 so that said dial can be rotated in opposite directions and said dial has graduations 16 on its upper face visible through an aperture 17 in the base plate 10.

A post 18 is adapted to be engaged by a 65 portion 19 of the lever mechanism to effect the disengagement of the lever mechanism with the dial. The above specifically mentioned elements do not in themselves constitute part of my present invention and are 70 described in full in my above mentioned patent:

In order to positively show that the score indicated through the aperture 17 is either plus or minus, I provide the following improved apparatus. The post 18 has an extension 20 which projects over a recess 21 formed in the under surface of the base plate 10 and this recess is made arcuate preferably concentric with the dial 11 as clearly 80 shown in Figs. 2 and 3. The plate 10 has a hole 22 which extends therethrough and a plate 23 slidably fits within the recess 21. The plate 23 is preferably made of resilient sheet steel and is bowed downwardly so as to 85 frictionally engage between the extension 20 of the post 18 and the inner surface 24 which forms the recess 21. The upper surface of the plate 23 has plus and minus symbols 25 and 26 formed thereon so that when the plate 90 is slid in opposite directions within the recess 21, the plus and minus symbols will be alternately visible through the hole 22 viewed from the upper face of the base plate 10.

The plate 23 on its lower surface has a 95 depending lug 27 adapted to be engaged by a projection 28 on the peripheral edge of the dial 11. The recess 21 is longer than the plate 23 as clearly shown in Figs. 2, 3 and 6 and during the rotation of the dial plate 100 in one direction, such for example as when a card player is using the apparatus to record a positive score, the projection 28 will engage the lug 27 and slide the plate 28 so that its plus symbol 25 will be visible 105 through the hole 22. This indicates that the graduation indicated through the aperture 17 represents a plus score. A continued movement of the dial in said direction will cause the projection 28 to slightly flatten 110 the bowed plate 23 and ride under the lug 27; it being noted that the sliding movement

of the plate 23 is comparatively small compared to the rotatable movement of the dial 11. Fig. 2 shows the projection 28 in a position about to engage the lug 27 of the plate 23, considering that the dial is being rotated in the direction of the arrow α and Fig. 3 shows the projection 28 having slid the plate to the opposite end of the recess and passed thereunder.

- 10 It will thus be noted that the symbol appearing through the hole 22 will remain in the place into which it is moved until the dial is again moved in an opposite direction to engage and slide the plate to the opposite 15 end of the recess. In this manner it is possible by a glance at the symbol appearing at the hole 22 for a person to determine whether the score indicated through the aperture 17 is plus or minus; thus avoiding discussion 20 during a card game and providing a check on the player.

By making the plate 23 bowed and of resilient metal and housing the major portion of said plate between the post extension 20 25 and the surface 24 of the recess 21, the plate 23 cannot be accidentally moved due to any vibration which might occur during the progress of the game. Fig. 4 shows the projection 28 in the position indicated in Fig. 3, and Fig. 5 shows the projection 28 in the act of riding past the lug 27 in which event the plate 23 is flattened to permit the projection 28 to pass thereby.

While I have described my invention as 35 taking a particular form, it will be understood that the various parts of my invention may be changed without departing from the spirit thereof, and hence I do not limit myself to the precise construction set forth, 40 but consider that I am at liberty to make such changes and alterations as fairly come within the scope of the appended claims.

Having thus described my invention, what I claim as new and desire to secure by 45 Letters Patent is:—

1. Apparatus of the character described including a supporting structure providing a slideway; a resilient slide in frictional en-

gagement with said slideway; and indicating means having a portion for engaging and moving said slide lengthwise of said recess and capable of compressing and thereby passing said slide, said slide having plus and minus symbols thereon; substantially as described. 50

2. Apparatus of the character described including a supporting structure providing a slideway; a resilient slide in frictional engagement with said slideway; and indicating means having a portion for engaging and 60 moving said slide lengthwise of said recess and capable of compressing and thereby passing said slide, said slide having plus and minus symbols thereon, said supporting structure having a hole therein through 65 which said symbols are alternately visible when said slide is moved in opposite directions by said portion of the indicating means; substantially as described.

3. Apparatus of the character described 70 including a base plate having a recess in its under surface; means extending across said recess and together therewith providing a slideway; a bowed resilient plate interposed within said slideway, said plate having a 75 hole leading to said recess, said plate having a lug projecting from its body portion; and an indicating dial having a projection adapted to engage said lug and slide said plate into abutment with opposite ends of the recess, 80 said projection, when the plate abuts an end of the recess, being capable of compressing said plate to pass by the lug, said plate having plus and minus symbols either of which is movable into alignment with said hole 85 according to the direction of the sliding movement of said plate; substantially as described.

In testimony whereof I have signed my name to this specification in the presence of 90 two subscribing witnesses.

EDWARD STEIGERWALD.
